UNITED STATES PATENT OFFICE.

ROMAN SOBOLEWSKI, OF CHICAGO, ILLINOIS.

BARK-STRIPPING MACHINE.

Application filed May 8, 1920. Serial No. 379,728.

To all whom it may concern:

Be it known that I, ROMAN SOBOLEWSKI, a citizen of the United States, and a resident of the city of Chicago, county of Cook, and

5 State of Illinois, have invented certain new and useful Improvements in Bark-Stripping Machines, of which the following is a specification.

10 My invention relates to new and useful improvements in bark stripping machines, and has for its object the provision of a machine of this character which will be simple and durable in construction, efficient in use and easily operated.

15 Another object is the provision of a bark stripping machine having a conveyer of means mounted on the conveyer for grasping and securely holding the material operated upon.

20 Another object is the provision of a bark stripping machine of means for automatically discharging the material operated upon after the same has passed through the machine.

25 Other objects appear hereinafter.

The invention consists in the combinations and arrangements in parts hereinafter described and claimed.

30 The invention will be best understood by reference to the accompanying drawings forming a part of this specification and in which,

Figure 1, is a side elevational view of the invention, and

35 Fig. 2, is a top plan view of the invention,

Fig. 3 is a sectional view taken on the substantially line 3—3 of Fig. 2,

Fig. 4, is a sectional view taken on the substantially line 4—4 of Fig. 2,

40 Fig. 5, is a front elevational view of the invention,

Fig. 6, is a fragmentary vertical sectional view of the elevation.

The invention is designed for use in strip-

45 ping the bark from twigs or saplings which are used in making wicker and willow work such as chairs, stands, etc. The invention is mounted upon a platform 8 which is supported by standards or legs 9. The pre-

50 ferred form of construction comprises a frame 10 which is mounted adjacent one end of the platform 8. Secured to the frame 10 by bolts 11 projecting therethrough is a suitable bearing 12 in which is journaled a

55 shaft 13. It of course is apparent that a frame 10 is mounted at each side of the

platform 8. Rigidly mounted upon the shaft 13 adjacent one end thereof and exterior of the frame 10 is a collar 14. At the opposite end of the shaft 13 is rigidly mounted a pulley or drive wheel 15 which is spaced from the frame 10 by a suitable collar 16. Rigidly mounted upon the shaft 13 adjacent one end thereof and interior of the frame 10 is a pinion 17. A similar pinion 18 is rigidly mounted upon the shaft 13 adjacent its opposite end and interior of the opposite frame 10 and spaced therefrom. Mounted upon the platform 8 intermediate the ends thereof at the opposite sides of the platform is a frame 19 provided with bearings which are spaced apart. Journaled in the uppermost of these bearings is a suitable shaft 20. Journaled at one side of the platform in the lower of these bearings is a shaft 21. At the opposite side of the frame journaled in the lower bearing of the frame 19 is a shaft 22. Rigidly attached to the shaft 20 adjacent one end thereof and interior of the frame 19 is a suitable gear wheel 22'. Rigidly mounted upon the shaft 20 adjacent its opposite ends and interior of the frame 19 is a pinion 23'. Journaled upon the shaft 21 in alignment with the pinion 22 is a gear wheel 23 the inner end of the shaft 21 being supported in a suitable bearing formed in a bracket 26 which is secured to the frame 8. Mounted upon the shaft 22 in alignment with the pinion 23 is a gear wheel 24, the inner end of the shaft 22 being journaled in a suitable bracket 25 mounted upon the frame 8. Mounted at the rearward end of the frame 9 at the opposite sides thereof are frames 27. Secured to each by suitable bolts 29 is a bearing 28 similar to the bearings on the forward end of the frame. Journaled in the bearing 28 is a shaft 30 mounted upon which interior of the frames 27 are gear wheels corresponding to and in alignment with the gear wheels 18 and 17. Suitable chain belts 31 and 30' are provided which are adapted to engage with the gear wheels provided upon the transversely extended shafts already described as will be readily understood. It is evident that one of the chains is at one side of the frame and the other chain at the opposite side extending the full length of the frame. Secured to the chains 30' and 31 and arranged transversely thereof are secured gripping plates which comprise a horizontally extended

portion 32 by means of which the same is secured to the chains 31 and 30' by bolting or other suitable manner and an arcuate portion 33 extends from portion 32 the arcuate portion 33 being adapted to engage the upper surface of the portion 32 of the forwardly adjacent plate.

Mounted upon the frame 8 at the forward end thereof is a U shaped supporting member 34 upon which is positioned at intervals suitable strippers 36, said strippers 36 being pivotally mounted in the brackets 35 secured to the member 34. The stripper 36 is formed from some spring rod material and comprises a substantially U shaped member the legs of which extend downwardly and are bulged or bent inwardly as at 37. As shown in Fig. 5, the portion between the member 35 and the portion 37 is curved to present the stripping portion proper forwardly of the side of 34. Legs of the stripper are retained in close relation by suitable spiral springs 38 which are secured at their opposite ends to the opposite legs of the stripper.

In operation the machine is driven by some suitable source of power which is connected to the drive wheel 15. By rotating wheel 15 the belt or conveyer comprising the chains and the grippers are caused to travel as will be readily understood. The material to be operated upon, that is the saplings or twigs, are inserted in the forward end of the machine between the legs of the stripper in that portion which extends below the inwardly bent portion 37. As will be noted when the chains are making the turn the grippers are disengaged from the adjacent gripper and the twig or sapling 39 is inserted between the legs as already described and enters the open end of the gripper 33. As the knife travels along it again assumes an engaged relation with the member 32 thereby securely clamping or binding the twig 39 in position. As this portion of the stripper at which the minimum space exists between the legs is substantially on the same plane as the plane of the upper portion of the chains forming the conveyer. Mounted upon the member 34 is a suitable stop 40 which extends transversely of the frame and projects forwardly of the support 34. The purpose of the member 40 is to limit the rearward swinging of the strippers.

While I have illustrated and described the preferred form of construction for carrying my invention into effect, this is capable of variation and modification without departing from the spirit of the invention. I,

therefore, do not wish to be limited to the precise details of construction set forth, but desire to avail myself of such variations and modifications as come within the scope of the appended claims.

Having described my invention, what I claim as new and desire to secure by Letters Patent is:

1. A bark stripping machine comprising a support having an endless belt mounted thereon; and a gripping member secured at an angle to, and overhanging said belt, adapted to travel with its secured end forward, and in a straight line of travel of the belt to approach same, but receding therefrom as said belt travels around a curve, substantially as described.

2. A bark stripping machine comprising a support having an endless belt mounted thereon; and spaced gripping members secured to, and overhanging said belt, and each other, and adapted in a straight line travel of said belt to approach same, and each other, so as to overlap, but receding from said belt and each other as said belt travels around a curve, substantially as described.

3. A bark stripping machine comprising a support having endless belts mounted thereon, and gripping members having their edges connected to said belts and the free edges thereof overhanging said belts so that in a straight line travel of the belts the free edge of one member approaches said belts and the top surface of an adjacent member but recedes therefrom as the belts travel around a curve, substantially as described.

4. A bark stripping machine comprising a support having endless belts mounted thereon; and gripping members arcuate in cross section having their edges connected to said belts and so arranged that in straight line travel of the belts the free edge of one member approaches the outside surface of an adjacent member but recedes therefrom as the belts travel around a curve, substantially as described.

5. A bark stripping machine comprising a support having endless belts mounted thereon; gripping members secured to and overhanging said belts and each other and so arranged that in straight line travel of the belts the free edge of one member approaches said belts and the top surface of an adjacent member but recedes therefrom as the belts travel around a curve; and stripping means co-operating with said gripping means, substantially as described.

6. A bark stripping machine comprising a support; endless belts mounted on opposite sides of said support; and gripping members having their edges connected to said belts, and the free edges thereof overhanging said belts and each other, so that in a straight line travel of the belts the free

- edge of one member approaches the belts and the top surface of an adjacent member but recedes therefrom as the belts travel around a curve, substantially as described; 5 a frame mounted on said support parallel with said gripping members; and U-shaped stripping members swingingly suspended on said frame and adapted to strip the bark from material drawn therethrough by said 10 gripping means, substantially as described.
7. A bark stripping machine comprising a support; endless belts mounted on opposite sides of said support; and gripping members having their edges connected to 15 said belts, and the free edges thereof overhanging said belt and each other, so that in a straight line travel of the belts the free edge of one member approaches the belts and the top surface of an adjacent member 20 but recedes therefrom as the belts travel around a curve, substantially as described; a frame mounted at one end of said support parallel to said gripping members; stripping members swingingly suspended from 25 said frame, the legs of said members being bent inwardly toward each other and adapt-
- ed to strip the bark from material drawn therethrough by said gripping members; a spring mounted between said legs for retaining same in close relation to each other; and a stop for arresting movement of said stripping member toward said gripping member, substantially as described. 30
8. A stripping machine comprising a support; a conveyor mounted on said support 35 and having grippers thereon; a frame mounted at one end of said support parallel to said grippers; U-shaped resilient members swingingly suspended on said frame and comprising spaced legs, the legs 40 of said members having a portion bent inwardly toward each other; and a spring adapted to retain the said legs in close relation to each other.

In witness whereof I have signed my 45 name to this specification in the presence of two subscribing witnesses.
